FIG. I.

FIG. 2.

INVENTOR
STEPHEN L. HEIDRICH

BY

Ernesto Gómez

ATTORNEY.

ELECTRO-ACOUSTIC HIGH IMPEDANCE TRANSDUCER

The present invention relates to sound translating devices, in general, and to electro-acoustic high impedance transducers which consist of an operable acoustic diaphragm with operating means in a housing enclosing air or a fluid containing suitable acoustic properties wherein the enclosed fluid provides an acoustical load to the operations of the diaphragm which opposes the applied power variations more or less as determined by the acoustical properties of the enclosed fluid, in particular.

Loud speaker enclosures commonly used are basically of two types: the completely enclosed type known as the infinite baffle enclosure, and vented type known as the reflex enclosure. The present invention relates to the infinite baffle or completely enclosed type. A characteristic of the infinite baffle is that the low frequency response capability is increased with an increase in size of the enclosed space. For a satisfactory response at 50 cycles this requires an enclosed space equivalent to approximately ten times the cubed nominal diameter of the acoustic diaphragm. If the enclosed space is packed with fiber glass, as disclosed in U.S. Pat. No. 2,775,309 to E.M. Villchur, an enclosed space equivalent to approximately two and one-half times the cubed nominal diameter of the acoustic diaphragm will produce an equally satisfactory response at 50 cycles, thus attaining a substantial reduction in size of the speaker enclosure. These devices are relatively low acoustic impedance devices because of the low impedance of large chambers.

The sound translating device disclosed in the Villchur patent may be regarded as utilizing an acoustic capacitance and an acoustical resistance couple or network, effective at low frequencies, in which the capacitance acoustically charged and discharged from applied fluid compressions and decompressions generated from the back of the related acoustic diaphragm is retarded by the acoustical resistance of a fiber glass packing therein effecting a time lag that may be considered analogous to certain R-C timing circuits used in certain electronic devices. The nature of the fiber glass resistance, however, is such that it is not effective as a means of further lowering the frequency response by means of increasing its density beyond a certain optimum for a given volume of enclosure.

The quest is for more compact and better speakers.

Accordingly, the present invention provides very compact loudspeakers or other electro-acoustic translating devices having a satisfactory wide frequency range of response with an enclosure that may be of appreciably less than one times the nominal diameter of the acoustic diaphragm cubed. The present invention, due to high pressures and small volumes, is herein regarded as a high impedance acoustic device, or sound cell because of the high acoustic impedance of the small chamber or chambers, and the high acoustic impedance of the duct.

It is one object of the present invention to provide an electro-acoustic high acoustic impedance transducer, wherein a satisfactory wide range of audio response from a suitable operable acoustic diaphragm mounted in a very compact housing or enclosure is obtained, in which small air chambers functioning as air capacitances are interconnected through an extraordinary high acoustic resistance due to viscosity in an air duct conductor defined by contiguously opposing walls of great area as compared with the cross-sectional area of the duct and in which the first capacitance in cooperation with the second of the air capacitances or, in other words, the acoustic regeneration chamber acts as an acoustic resistance-capacitance network couple that reacts favorably to low frequency cycles of compression and decompression that are impressed via that first or acoustic pressure generation chamber from the back of a related acoustic diaphragm.

The present invention is also directed to electro-acoustic transducers in general, of the completely enclosed or infinite baffle type containing a resurgent high pressure acoustic system in which a high acoustic resistance is coupled with rela-

tively small acoustic capacitances for response to lower frequencies of the acoustic spectrum of the general type as disclosed in my copending U.S. Pat. applications, Ser. No. 629,623, filed Apr. 10, 1967, entitled "Electro-Acoustic Transducer", and Ser. No. 619,658, filed March 1, 1967, now abandoned entitled "Electro-Acoustic Transducer", and in my U.S. Pat. No. 3,324,966, granted June 13, 1967, entitled "Electro-Acoustic Transducer", and No. 3,317,000, granted May 2, 1967, entitled "Electro-Acoustic Transducer".

In the aforementioned there are disclosed enclosed acoustical systems in which the related acoustic diaphragm is predominantly controlled by the acoustic characteristics of the enclosed air or fluid in the housing according to the properties of a system of acoustic elements consisting of fluid compliance, resistance and mass contained in an arrangement of chambers and connecting duct or ducts, which improves the fidelity of the reproduced sound corresponding to the variations of electrical input.

As disclosed therein, the principal feature is in the utilization of the resurgence of acoustic energy from a highly compressed fluid in a small secondary chamber controlled through a high fluid flow resistant duct back to the primary chamber or enclosure, in which the acoustic pressure variations are generated on the back of the related acoustic diaphragm, thereby causing the fluid resurgence to react effectively on the back of the acoustic diaphragm increasing the efficiency of operation, that is, an acoustic resistance-compliance network designed to reproduce optimum acoustic response comparable to the electrical input.

In particular, the low frequency response capability of the infinite baffle is increased, for a decrease in the acoustic capacitance heretofore contained in the enclosure, for very compact loudspeakers or receivers. This is achieved as indicated, with an operative acoustic diaphragm mounted in a small housing in which two very small air chambers, functioning as air capacitances, are interconnected by an extraordinarily high acoustic resistance in the form of a high resistance air duct conductor of substantial area relative to its width between walls, which in cooperation with one of the two air capacitances acts as an acoustic resistance-capacitance network couple, that reacts favorably to low frequency cycles of compression and decompression that are impressed via the first chamber from the back of a related acoustic diaphragm.

The specific embodiments disclosed in U.S. Pat. No. 3,317,000 consist of an arrangement of contiguous walls forming an air conductor passage which is generally peripheral to the unit and axially disposed thereto, with the second or outer chamber located entirely rearwardly of the inner chamber. The specific constructions disclosed in U.S. Pat. No. 3,324,966 consist of an arrangement of contiguous walls forming an annularly radial fluid medium passage disposed perpendicularly and radially to the unit; and wherein further, two annular chambers are formed about the magnetic structure of the unit, permitting compact loudspeaker systems, with the second chamber located entirely rearwardly of the inner chamber. The copending patent applications generally disclose an arrangement of wall means disposed in an enclosed space at the back of the diaphragm, which wall means may also include the fluidtight enclosure, or be separate therefrom, and which wall means forms contiguous radial walls defining a narrow radial or annular space therebetween, which narrow space communicates with the fluid medium in the enclosed spaces, and with the second chamber substantially smaller than the first chamber, and located entirely rearwardly and substantially radially inwardly relative to the inner chamber.

In all my patents and copending patent applications, the second or remote chamber is smaller or at least no larger than the inner chamber and located rearwardly relative thereto, and the inner or first chamber adjacent the diaphragm is located, at least in part, annularly about the second chamber, with the latter being inwardly disposed in its entirety relative to the annular or surrounding part of the first chamber.

However, particularly, the present invention is directed toward constructional and operational improvements in duct transducer devices providing still better performance and compactness and adaptability to various applications.

It is an object of the present invention to provide electro-acoustic transducers having an inner chamber adjacent the diaphragm and an outer chamber communicating therewith through a high resistance duct, the outer chamber being positioned rearwardly and/or at least in part annularly around the inner chamber and approximately equal to or substantially larger in volume than that of the inner chamber.

It is another object of the present invention to provide electro-acoustic transducers in accordance with the above mentioned objective wherein the outer chamber is at least partly located annularly about the inner chamber for the purpose of a thin flat construction.

It is another object of the present invention to provide electro-acoustic transducers in accordance with the above mentioned objectives wherein the high resistance duct is axially arranged.

With these and other objects in view which will become apparent in the following detailed description, the present invention will be clearly understood in connection with the accompanying drawings, in which:

FIG. 1 is an axial section of an acoustic transducer designed in accordance with the present invention; and

FIG. 2 is an axial section of another embodiment of an acoustic transducer in accordance with the present invention.

Referring now to the drawings and in particular to FIG. 1, the electro-acoustic transducer of the present invention comprises a conventional dynamic loud speaker unit consisting of a conical acoustic diaphragm 1 suspended by a compliant peripheral flange 2 cemented to a supporting rim 3 of a basket 4 of a magnetic structure 5 actuated by a voice coil 6 which operates in a magnetic gap 7 in the magnetic structure 5, and provided in a housing enclosure which includes a rear circular wall 9 spaced axially and parallel to a front annular wall 8 and which also includes an outer peripheral cylindrical wall 10 having circumferential grooves 10a and 10b in which the enclosure walls 8 and 9, respectively, are sealingly secured.

A toroidal solid member 11 having a substantially square cross section (although not limited thereto) is disposed coaxially about and sealingly against the outer peripheral surface of the magnetic structure 5. The outer and inner peripheral surfaces 11a and 11b, respectively, of the member 11 are cylindrical and coaxially oriented relative the unit.

A relatively thin cylindrical wall baffle member 12 extends sealingly from the rim 3 of the basket 4 rearwardly short of the rear wall 9 and is coaxially oriented relative the unit and spaced slightly apart and around the outer peripheral surface 11a of the solid member 11.

The cylindrical member 12 thereby is positioned with its inner cylindrical surface 12a coaxially aligned parallel and spaced from the outer cylindrical surface 11a of the member 11, forming therewith an axial circumferential channel 13. Members 11 and 12 divide the diaphragm enclosed housing into a first or inner chamber 14 adjacent the diaphragm, and a diaphragm chamber or second or remote outer chamber 15, both chambers in fluid communication via the axial channel or duct 13.

As clearly disclosed in FIG. 1 of the drawing, the outer chamber 15 is annular, surrounding entirely the inner chamber 14, and is bounded by the enclosure's walls 8, 9 and 10 and by member 12 and the basket rim 3, whereas the inner chamber 14 is defined by the member 12, the basket rim 3, the diaphragm 1 and the front surface 11c of the solid member 11, the latter chamber being substantially triangular in cross section.

In accordance with the present invention, the inner chamber 14 is preferably for wide range reproduction smaller in volume than that of the outer chamber 15.

In the embodiment illustrated in accordance with the present invention, the rim 3 of the basket 4 is formed in a plu-

rality of preferably three steps or angular rim portions 3a, 3b and 3c, respectively. Against the inner angular rim portion 3a is disposed sealingly the front end of the cylindrical member 12. The compliant peripheral flange 2 of the diaphragm is cemented to the intermediate rim portion 3b of the basket 4, and the outermost rim 3b of the basket 4 is sealingly secured to the inner portion of the front enclosure wall 8. The rim 3 sealingly separates the chambers 14 and 15, and isolates the chamber 14 from the ambient.

10 In accordance with the present invention, the front housing wall 8 extends radially sufficiently outwardly to define the outer chamber 15 to be relatively large in volume with respect to the inner chamber 14. The outer chamber 15 extends completely annularly around, as well as rearwardly, the inner chamber 14.

15 The solid member 11, being in a fluid-tight forced fit with respect to the magnetic structure 5, insures that there is no fluid leakage between the chambers 14 and 15 through the interface (surface 11b) thereof.

20 Fiber glass packing 16 may be provided optionally within the chambers 14 and/or 15 to optimize the density for suitable damping.

25 Spacing elements (not shown) may be used between the baffle member 12 and the outer peripheral surface 11a of the solid member 11 to insure the proper duct spacing. In accordance with the present invention, there is thereby formed a back loading acoustic resurgence network assembly, constituting a pair of cylindrical surface cooperating members spaced coaxially, and together with the housing enclosure rim 3 and the diaphragm 1, define the inner chamber 14, immediately adjacent and behind the diaphragm, and the outer annular fluid resurgence chamber 15 annularly disposed about chamber 14 about the member 12, both chambers communicating with each other via the axially circumferential duct 13 between the members 11 and 12.

30 This permits a fluid medium behind the diaphragm 1 to pass only between the chambers or cavities 14 and 15 through the axially disposed circumferential duct 13.

35 40 The relative sizes of the chambers 14 and 15, respectively, are of importance to the function of the device, although the invention is not restricted thereto. The acoustic resurgence network assembly of the present invention provides the secondary chamber 15 as a relatively low compression chamber, with the high resistance duct or conduit 13 communicating the chamber 15 with the chamber 14.

45 50 With the structure of the present invention and the rear wall 9 disposed immediately behind the rear end of the magnetic structure 5 and the outer chamber 15 being annularly provided thereabout, space requirements are minimized especially the thickness of the unit.

55 In operation, the movements of the diaphragm 1 impelled by the energized voice coil 6, generate compressions and decompressions of the air in the chamber 14, which being of a small volume, causes plus and minus pressures to attain exceptionally high degrees above and below the atmosphere pressure, and thereby provides an air stiffness and control over the movements of the diaphragm 1, which predominates over the mechanical stiffness of the compliances of the diaphragm 1. The air stiffness thereby takes over much of the inertia of the moving parts. The small volume of chamber 14 relative chamber 15 provides further efficiencies.

60 65 The air duct or conduit 13 slowly releases the higher pressures in the chamber 14, which are generated increasingly with decrease of frequency to chamber 15, where plus and minus pressures are regenerated again, but with a time lag as compared with the pressures prevailing in the inner chamber 14 and reach a peak when the incoming air pressures through 70 the air duct 13 become equal to the air pressures in the chamber 15. The regenerated pressures in the chamber 15, which act as an acoustic regenerating or reflection unit for low frequencies, become slowly resurgent with the reversal of air flow adding the released power resurgence through this air duct 13 to the back of the acoustic diaphragm 1 at a frequency

compatible to that in the acoustic resistance-capacitance network couple of the air duct 13 with the chamber 15. The relatively large size of the rear chamber 15 with respect to the inner chamber 14 provides this slower resurgence than heretofore.

Because of the small housing desired for such a loudspeaker, the acoustic capacity of chambers 14 and 15, are comparatively minute and the complementary acoustic resistance necessary to achieve a low frequency resurgence of 50 cycles or less is extraordinarily great. The high acoustic resistance is achieved in accordance with the extremely close contiguous radial spacing, that is, in the order of a few thousandths of an inch to one hundred thousandths, more or less, depending upon the size of the reproducer, between the cylindrical surfaces 11a and 12a of the cooperating members 11 and 12, respectively, which define the air duct conductor 13, thus providing the means for attaining an extraordinarily high acoustic resistance in the great area of the duct conductor 13. With this arrangement there is applied a high pressure by virtue of the small capacitances, resistance controlled acoustic loading system, in which the acoustic resistance is very great and is an effective retarding element, as well as of economical construction, to the flow of air between the two relatively small chambers 14 and 15. Such highly acoustic resistance is obtained by the annular air duct 13 of the viscosity effect of extensive surface area as compared to the cross-sectional area of the duct. Accordingly, a high pressure resistance controlled regenerative acoustic loading system is achieved, acting on the back of the acoustic diaphragm, in which a high acoustic resistance is provided with the great viscosity residing in a thin axially aligned air duct conductor formed intermediate the coaxial cylindrical contiguous surfaces 11a and 12a of substantial length as compared to the cross-sectional area of such air duct conductor.

The solid member 11 serves not only with its surface walls defining the inner surface of the air duct 13, and the rear surface 11c of the inner chamber 14, but also acts as a filler member filling an annular portion of the space in the housing enclosure space immediately behind the inner chamber and inwardly of the outer chamber 15, and may be readily, cheaply and inexpensively manufactured.

Referring now to the drawings and in particular to FIG. 2, another embodiment of the present invention is illustrated with like numerals referring to similar portions described already in connection with FIG. 1. In this embodiment of the loud speaker, an innermost cooperating duct member 17 is provided, having an L-shaped cross section, and is annular in configuration, having an annular wall 18 and a cylindrical wall 19 perpendicular thereto. The member 17 is disposed sealingly in fluid tight engagement against the magnetic structure 5 at the inner circumference of the annular wall 18.

The cylindrical wall 19 of the member 17 is oriented coaxially relative the unit and spaced coaxially inwardly relative baffle member 12. The annular wall 17 defines the spacing between the outer peripheral cylindrical surface 19a of the cylindrical wall 19 and the inner peripheral surface 12a of the member 12. Spacers (not shown) may also be used.

The wall 17 is disposed at the front end of the magnetic structure 5 with the wall 19 extending rearwardly therefrom at the outer circumferential edge of the wall 17, and terminates at rear end 19b short of the rear housing wall 9'. Accordingly, there is formed a space or chamber portion or part 15b rearwardly of the annular wall 18 and bounded by the annular wall 18, the magnetic structure 5 and by and inwardly of the cylindrical wall 19 of the member 17, and which chamber portion 15b is in communication with the chamber portion 15a (similar to chamber 15 of FIG. 1 but smaller) defined between the housing walls 8', 9' and 10, the chamber portions 15a and 15b constituting the second or outer chamber divided into two annular parts freely (without substantial resistance) in communication via rear communicating space 20 (between the wall 9' and the rear edge 19b of cylindrical wall 19).

The inner chamber 14 in the embodiment of FIG. 2 is similar to the inner chamber 14 of FIG. 1 in shape and size. The outer chamber 15a, however, is substantially smaller than the chamber 15 of FIG. 1 and accordingly the enclosure walls 8' and 9' can be smaller in diameter, since chamber portion 15b further constitutes the remainder of the outer chamber and serves to reduce the overall diameter of the entire unit.

The relative sizes of the inner chamber 14 and the outer chamber (constituting portions 15a and 15b), respectively, are of importance to the functioning of the device. The volume of the chamber 14 is a fraction of the volume of the outer chamber 15a and 15b. The acoustic resurgent network assembly of the embodiment of FIG. 2 provides a high compression chamber, namely chamber 14, and a high resistance conduit 13 between the inner chamber 14 and the outer chamber (15a and 15b together).

In operation the movements of the diaphragm 1 impelled by the energized coil 6 generate compressions and decompressions of air in the chamber 14 which, being of small volume, cause plus and minus pressures to attain exceptionally high degrees above and below the atmosphere pressures and, thereby, provide an air stiffness and control over the movements of the diaphragm 1, which tends to predominate over the mechanical stiffness of the compliances in the diaphragm 1. The air stiffness thereby takes over much of the inertia of the moving parts. The air duct conductor 13 slowly releases the higher pressures in the chamber 14, which are generated increasingly with decrease of frequency to the outer annular fluid resurgence chamber 15a and 15b, where plus and minus pressures are regenerated again, but with a time lag as compared with the pressures prevailing in the first chamber 14, and reach a peak when the incoming air pressures through the air duct conductor 13 become equal to the air pressures in the outer chamber 15a and 15b. The regenerated pressures in the outer chamber, which act as an acoustic regenerating or reflecting unit for low frequencies, become resurgent with the reversal of air flow adding the released power of resurgence through this air duct conductor 13 to the back of the acoustic diaphragm 1 at a frequency compatible to that in the acoustic resistance-capacitance couple of the air duct conductor 13 with the air chamber 15a and 15b.

The embodiment of FIG. 2 provides, in effect, a hollow portion or space (which was filled in FIG. 1 by the solid member 11) and thereby permits reduction of the diameter of the entire unit while, at the same time, permitting the ratio of the combined outer chamber (15a and 15b), the chamber 15 being now a portion of the outer chamber, to be much greater than that of the inner chamber 14, providing the exceptional loudspeaker performance in accordance with the present invention.

The high acoustic resistance is achieved in accordance with the extremely close contiguous axial spacing, that is, in the order of a few thousandths of an inch, for extremely small units extending over the range of about one half of a thousandth, as might be for a minute hearing aid, to about one hundred thousandths of an inch, preferably about .06 inch, more or less, for a 4 inch diameter speaker unit, between the surfaces 12a and 19a, respectively, which define the air duct conductor 13, thus providing the means for attaining an extraordinarily high acoustic resistance in the great area of surface viscosity provided as compared to the minute cross-sectional area of the duct conductor 13.

Fiber glass packing 16 may be provided optionally in chambers 14 and/or 15a and/or 15b to optimize the density for suitable damping.

With this arrangement there is applied a high pressure by virtue of the small capacitances, resistance controlled acoustic loading system in which the acoustic resistance is very great and is an effective retarding element, as well as of economical construction to the flow of air between the two relatively small chambers, in which the second chamber is substantially larger than the volume of the inner chamber. Such high acoustic resistance is obtained by the axial air duct 13 of the viscosity ef-

fect of extensive surface area as compared to the cross-sectional area of the duct. Accordingly, a high pressure resistance controlled regenerative loading system is achieved acting on the back of the acoustic diaphragm, in which a highly acoustic resistance is provided in the great viscosity residing in a thin axially oriented air duct formed intermediate the axial cylindrical contiguous surfaces of walls of substantial lengths as compared to the cross-sectional area of such air duct.

It is to be understood that other embodiments are possible, and that the scope of the present invention also may include various acoustic devices employing an operative acoustic diaphragm, the back of which acts on a system of two small interconnected chambers in which the generated and regenerated acoustic resurgences from one to the other are controlled by a dominating high acoustic resistance in an air duct conductor defined by adjacent disposed wall surfaces of an extensive area, as compared with the cross-sectional area of the duct with the outer or second chamber being substantially greater in volume than that of the inner chamber. It is further understood that the term air is analogous with any fluid medium, and the use of lighter or heavier than air fluid mediums in the resistance-capacitance system described, are within the scope of the present invention.

The present invention further provides in an electro-acoustic transducer, a device consisting essentially of a Helmholtz resonator comprising a cavity having the equivalent of a long tubular extension in the form of a thin duct the outer terminus of which is open peripherally to another cavity into which acoustic pressure variations are generated by an acoustic diaphragm fitted air tight into an opening therein, and means to operate the diaphragm.

An electro-acoustic transducer comprises an operative acoustic diaphragm enclosed on one side with a small acoustic cavity resonant to upper audio frequencies, the cavity peripherally relieved of the pressures of the lower frequencies by being in communication peripherally with the open end of the equivalent of the tube in a Helmholtz resonator resonant to lower audio frequencies, and the combined resonances helping to control the diaphragm to follow the variations of mixed frequencies of electrical input.

If the second cavity, the Helmholtz equivalent, is smaller than the first or input cavity, the upper the frequencies will predominate.

If the second, or Helmholtz cavity is larger than the first or input cavity, the lower frequencies will predominate.

In either case the first or input cavity would cover the area of the acoustic diaphragm, but in depth would be only a fraction of the diametrical dimension of the diaphragm, that is the depth of the first cavity would be preferably one-fourth of the diametrical dimension of the diaphragm or even less.

By virtue of its smallness, the first cavity is resonant to the higher frequencies.

By virtue of the Helmholtz effect produced by the second cavity in cooperation with the thin duct open at its terminous to the periphery of the first cavity, resonance to lower frequencies is provided.

If the cavity of the Helmholtz resonator is empty, the resonant frequency will be peaked. If the cavity is packed with fiber glass to optimum density, the lower frequency resonance peak is broadened which is desirable.

I claim:

1. An electro-acoustic device comprising:

a housing;

an axial operating means including an acoustic diaphragm and a magnetic structure generating acoustic pressure variations to a free fluid medium on one side of said acoustic diaphragm and for generating corresponding acoustic pressure variations to a fluid medium enclosed in said housing on the other side of said acoustic diaphragm; said housing on the other side of said acoustic diaphragm being fluidtight and defining an enclosed space; wall means disposed within said enclosed space being two contiguous walls defining a narrow air duct intermediate

said contiguous walls and dividing said enclosed space into a diaphragm chamber adjacent said acoustic diaphragm and a second or outer chamber; said narrow air duct in fluid communication between said diaphragm and second chambers; and said second chamber is at least in part annularly arranged about said diaphragm chamber.

5 2. The electro-acoustic device, as set forth in claim 1, wherein said second chamber further extends rearwardly relative said diaphragm chamber.

10 3. The electro-acoustic device, as set forth in claim 2, wherein said second chamber is substantially entirely arranged annularly with respect to said diaphragm chamber.

15 4. The electro-acoustic device, as set forth in claim 3, wherein said wall means includes a solid toroidal member disposed coaxially and rearwardly of said diaphragm chamber, filling the space directly therebehind, and positioned against said magnetic structure and defining on one surface thereof the rearmost surface of said diaphragm chamber.

20 5. The electro-acoustic device, as set forth in claim 4, wherein said member is substantially rectangular in cross section.

25 6. The electro-acoustic device, as set forth in claim 5, wherein said wall means further includes a cylindrical regenerating means coaxially arranged about said member and spaced therefrom.

30 7. The electro-acoustic device, as set forth in claim 6, wherein said regenerating means comprising a cylindrical baffle further extending forwardly relative said member, separating thereat said diaphragm chamber from said second chamber.

35 8. The electro-acoustic device, as set forth in claim 1 wherein said second chamber is in substantial part arranged annularly about said diaphragm chamber defining at least partly an outer part of said second chamber, and said second chamber further is in substantial part located directly behind said diaphragm chamber immediately about said magnetic structure defining an inner part of said second chamber.

40 9. The electro-acoustic device, as set forth in claim 8, wherein said wall means include a member with an annular radially oriented wall disposed coaxially and rearwardly of said diaphragm chamber and against and about said magnetic structure at the forwardmost portion thereof, thereby separating the rear of the diaphragm chamber from said inner part of said second chamber directly therebehind.

45 10. The electro-acoustic device, as set forth in claim 9, wherein said member has an L-shaped cross section with an outermost cylindrical wall extending rearwardly from the outer circumferential edge of said annular radially oriented wall, and surrounding said inner part of said second chamber, and said wall means further includes a cylindrical baffle, coaxially arranged about said cylindrical wall and spaced therefrom, defining therebetween said narrow air duct and separating thereabout said outer part of said second chamber.

50 11. The electro-acoustic device, as set forth in claim 10, wherein said cylindrical baffle further extends forwardly relative said cylindrical wall, separating thereat said diaphragm chamber from said outer part of said second chamber, and said cylindrical baffle and said cylindrical wall spaced at their rear ends from the rear of said housing, thereby communicating said inner part of said second chamber and said outer part thereof directly adjacent the rear end of said narrow air duct.

55 12. The electro-acoustic device, as set forth in claim 11, wherein said outer part of said second chamber is of greater volume than that of said inner part of said second chamber.

60 13. The electro-acoustic device, as set forth in claim 12, wherein said housing comprises a rear circular wall coaxially arranged relative, and spaced rearwardly behind near said magnetic structure, a front annular wall coaxially arranged about the edge of said acoustic diaphragm, and an outer cylindrical housing wall having front and rear circumferential grooves on its inner surface adjacent its respective ends, and said front annular wall and said rear circular wall disposed 65 sealingly in said front and rear grooves, respectively.

14. The electro-acoustic device, as set forth in claim 1, wherein said wall means are arranged so that said narrow air duct is axially positioned.

15. The electro-acoustic device, as set forth in claim 14, wherein said housing including an outer cylindrical housing wall, said wall means includes a cylindrical baffle inwardly spaced coaxially relative said outer cylindrical housing wall, defining, at least in part, said second chamber therebetween and separating said first chamber inwardly located relative thereto, and defining said axially positioned narrow air duct communicating said diaphragm and second chambers.

16. The electro-acoustic device, as set forth in claim 15,

wherein said wall means further includes a member having an outer cylindrical surface spaced inwardly from said baffle, defining said narrow air duct therewith, and defining the rear surface of said diaphragm chamber.

17. The electro-acoustic device, as set forth in claim 16, wherein said member is solid, filling the space behind said diaphragm chamber.

18. The electro-acoustic device, as set forth in claim 16, wherein said member defines a space inwardly therefrom and 10 behind said diaphragm chamber, constituting a portion of said second chamber.
